SIGNORS TO THE NEW IDEA SPREADER CO., OF COLDWATER, OHIO, A CORPORATION
OF OHIO.

GEAR CASE.

Original application filed September 22, 1925, Serial No. 57,877. Divided and this application filed April 26,
1927. Serial No. 186,755.

This application is a division of an application filed by us September 22, 1925, Patent No. 1,645,252, issued Oct. 11, 1927.

The present invention relates particularly to means for housing the lower ends of corn-husking rolls, or analogous work-performing elements, and the gearing connected therewith, the object being to protect the gearing from damage by falling objects, permit them to run in oil, and to afford ready access to them for cleaning or repairs. The invention is illustrated in the accompanying drawing and will be hereinafter fully set forth.

In the drawing, Fig. 1 is a plan view of mechanism embodying the present invention.

Fig. 2 is a detail section on the line 2—2 of Fig. 1.

Fig. 3 is a longitudinal section on the line 20 3—3 of Fig. 1.

Fig. 4 is a detail view of a bracket constituting the end member of a roll-supporting yoke.

A portion of a husking roll is shown at 8, 25 and it will be understood that the rolls are arranged in pairs and that the adjacent surfaces of members of each pair move downwardly, the husks being caught by the rolls and passed between them while the stripped ears are passed longitudinally over the rolls and delivered at the end of the machine. Motion is imparted to the rolls through 30 gearing at the upper ends of some of the rolls and the lower ends of the rolls are operatively connected through spur gears 24 secured on trunnions 25 in which the respective rolls terminate.

Secured upon and extending across the husking machine frame are yokes which 40 carry the bearings for the several rolls, the yokes being provided at both the upper and lower ends of the snapping rolls as well as the husking rolls. Each yoke consists of a lower bar 26 which is secured rigidly to the frame of the corn-husking machine, and an upper bar 27 which may be of the same form and dimensions as the lower bar and is arranged parallel therewith. The trunnions or shafts of the rolls are journaled in bearing blocks or boxes 30 which fit closely between the yoke members 26 and 27, and that block or box which receives the trunnion or journal of the outer roll has its upper and

lower sides grooved whereby it may slidably engage the yoke bars 26 and 27. The block 55 or box receiving the trunnion or shaft of the inner roll is, however, held against lateral movement by the stay bolts 31 inserted through the said bars adjacent the sides of the box. It will be readily understood that by this arrangement the outer roll may yield to the thickness of a stalk or other article passing between the rolls so that the proper operation of the parts will be effected and the usual springs (not shown) are provided to 60 maintain the operative relation of the rolls.

To close the ends of the yokes, we employ brackets 67, one of which is shown in detail in Fig. 4. This bracket is a single integral casting including a short standard 68, a lateral base plate 69 at the lower end of the standard, and flat leaves 70 on its inner side at its upper and lower ends, a threaded opening 71 being formed through the standard. The ends of the yoke bars rest upon and are 75 bolted to the leaves 70, and the base 69 rests upon and is bolted to the side bars of the machine frame, the opening 71 providing a bearing for the spring-adjusting screw. This construction is strong and permits the yoke 80 to be assembled before being placed in the machine inasmuch as the securing bolts are not inserted through the lower yoke bars but are inserted through the base plates 69 at one side of the yoke bars.

The ends of the gear case are secured to right angle brackets 83 which are in turn secured to the side bars 1 of the machine frame. Other brackets 84 are secured to the frame by the same bolts that secure the 90 brackets 83 thereto and rise at the front of the case to carry a cross rod 85. The case comprises a back plate 86 provided with openings whereby it may be fitted on the trunnions at the lower ends of the husking 95 rolls, against the bearings therefor and between the bearings and the gears. The case also includes a box or trough consisting of a short back wall 87, a bottom 88, a front wall 89, and end walls 90 integrally united. In assembling these parts, the trunnions of the husking rolls are engaged through the bearing blocks in the yoke, and the back plate 86 is slipped on the ends of the trunnions. The gears are then secured on the 100 ends of the trunnions, the plate 86 being 105

thereby retained in place, after which the case or trough, with lubricant in it and the brackets 83 secured thereto, is raised into position so that the back plate 86 will pass 5 into the case in front of the short back wall 87, the brackets 83 being then bolted rigidly to the main frame. The cover 91 consists of a plate of proper dimensions to extend over the entire case and the yoke and 10 may be rigidly secured upon the yoke by the stay bolts 31 therein. The ear-guiding fingers 66 are permanently attached to the cover at the back end thereof, and the lower ends of the divider bars 92 are also secured 15 upon the cover at the back edge thereof, although other means for guiding the discharging ears may be provided. The cover is also provided with openings 93 giving access to the oil cups 94 in the bearings 30 20 whereby lubricant is supplied to the bearings. The front edge of the cover has rolled portions 95 encircling the rod 85 so that the cover is firmly supported in its proper position, and on the under side of the cover is 25 secured a strip 96 which returns to the case any grease thrown up by the gears 24 and the respective retaining cotter pins and prevents such grease running along the cover. The upper portion of the front wall 89 is 30 bent toward the gears, as at 97, to prevent grease being thrown out by the centrifugal action and also to provide space for the rod 85.

The husked ears pass over the cover 91 35 into a chute 98 which directs them into a conveyer by which they are carried to a bin or other receptacle. The chute is shown as hingedly supported on the rod 85 and its front end may be suspended from the operator's platform by a chain 99 so that it may be raised and prevented from digging into the bottom of the conveyer when the latter is folded.

Grease is fed into the case through an 40 opening in the top thereof which is normally closed by a cover 100.

It will be noted that the gears are entirely enclosed and may run in oil. If the bolts securing the brackets 83 and 84 to the frame 45 be removed, the gear case may be withdrawn downwardly, without disturbing the gears or the cover which will be supported on the yoke, and the changing of the oil or cleaning of the case is thus facilitated. When thus 50 removing the case or trough, the chute may be swung upwardly and rearwardly to rest upon and be supported by the cover.

Having thus described the invention, we 55 claim:

1. In a corn-husking machine, the combination with driven rotatable elements, and gearing connecting the ends of said elements, of a shield extending over the gearing, and a gear case completely housing the gearing below the shield, the shield constituting a

cover for and being secured independently of the case and the case being movable upwardly into position around the gearing and removable downwardly from the gearing.

2. In a corn-husking machine, the combination of a yoke carrying bearings for driven rotatable elements, gearing connecting the ends of said elements, a back plate fitted on the ends of the driven elements and disposed between the gearing and the bearings 70 in the yoke, a gear case having an open top and movable upwardly to extend around the back plate and the gearing, and a cover extending over the case and the yoke and secured independently of the case. 80

3. In a corn-husking machine, the combination of a yoke carrying bearings for driven elements, gears connecting the ends of said elements, a back plate fitted on the ends of the driven elements between the yoke 85 and the gears, a gear case acting with the back plate to house the gears, and a cover extending over the case and the yoke, there being an oil deflecting strip on the under side of the cover within the case. 90

4. In a corn-husking machine, the combination of a yoke carrying bearings for driven elements, gears connecting the ends of said elements, a back plate fitted on the ends of the driven elements between the yoke and 95 the gears, a gear case acting with the back plate to house the gears, and a cover extending over the case and the yoke, the upper portion of the front wall of the case being 100 bent toward the gears.

5. In a corn-husking machine, the combination of a supporting frame, a yoke carrying bearings for driven elements and secured upon the frame, gearing connecting the elements below the yoke, a back plate spanning 105 the driven elements between the yoke and the gearing, a case housing the gears and secured upon the frame below the gears, and a cover extending over the case and the yoke and secured independently of the case, the 110 case being removable to leave the cover and gears intact with the back plate.

6. The combination of a yoke, journal boxes mounted in the yoke, rotatable elements having trunnions extending through 115 the journal boxes, intermeshing gears on the trunnions, a back plate fitting on the trunnions between the gears and the yoke, and an open-top case housing the gears and having a back wall projecting upwardly between the back plate and the yoke. 120

7. The combination of a yoke, journal boxes mounted in the yoke, rotatable elements having trunnions extending through the journal boxes, intermeshing gears on the 125 trunnions, a back plate fitting on the trunnions between the gears and the yoke, an open-top case housing the gears and having a back wall projecting upwardly between the back plate and the yoke, and a cover plate 130

extending over the case and the yoke and closing the case, the cover and the case being independently secured.

8. The combination of a supporting frame, 5 brackets consisting of a standard, a base plate disposed laterally of the standard and secured upon the frame and vertically spaced leaves on the inner side of the standard, a yoke consisting of upper and lower bars secured to the respective leaves of the brackets, bearings in the yoke, rotatable elements journaled in and extending through the bearings, gearing connecting the ends of said elements, a case secured on the frame below 10 the gearing and extending around the gearing, and a cover secured upon the yoke and extending over the case to close the same.

9. The combination of a supporting frame, a yoke thereon, bearings in the yoke, rotatable elements having end portions journaled in and extending through the bearings, gearing connecting the ends of the elements, a back plate fitted on the ends of the said ele- 20

ments between the gearing and the bearings, a case consisting of a bottom, sides and ends enclosing the gearing and the lower portion of the back plate and secured to the frame below the gearing, and a cover extending over the top of the case and the back plate and secured independently of the case. 25 30

10. The combination of a yoke, bearings in the yoke, rotatable elements journaled in and extending through the bearings, gearing connecting the ends of said elements, a back plate fitted on the ends of the elements between the gearing and the bearings, a case fitting around the gearing and the lower portion of the back plate, and a cover extending over the yoke and the case and provided on its under side within the case with 35 40 means for deflecting oil thrown from the gearing.

In testimony whereof we affix our signatures.
